(57) **CLAIM**

The ornamental design for a game tile, as shown and described.

DESCRIPTION

This invention was made with Government support under Award No. 1346821 awarded by the Small Business Innovation Research (SBIR) program of the National Science Foundation (NSF). The Government has certain rights in the invention.

FIG. 1 is a top right perspective view of a game tile showing our new design;

FIG. 2 is a front view thereof;

FIG. 3 is a top view thereof;

FIG. 4 is a bottom view thereof;

FIG. 5 is a left side view thereof; and,

FIG. 6 is a right side view thereof.

The broken lines show portions of the game tile which form no part of the claimed design.
